UNITED STATES PATENT OFFICE.

EDWARD A. EVERETT, OF LONG ISLAND CITY, NEW YORK, ASSIGNOR TO NANDE CORPORATION, A CORPORATION OF NEW YORK.

MACHINE FOR WORKING ON RAILS.

Application filed July 30, 1923. Serial No. 654,789.

This invention relates to machines for working on rails such as the rails of a railway track, or I-beams or girders used in structural steel, and has for an object to 5 provide a machine with a spindle that may carry a tool for working on the side of the rail or girder, a machine of this type that may be rolled along the rail from place to place, a machine that has a working arm 10 capable of being brought into position as required, a machine that can be applied to work on both sides of the rail, a machine in which the working tool is driven through a friction clutch, a machine which is operated by power and in which the force applied to the working tool is regulated by a manually operated lever and a machine which is adapted for tightening bolts. These and other objects of the invention 15 will be more fully understood from the following specification and the accompanying drawings forming a part of the specification, and in which Fig. 1, is a side view of my improved machine in place on the rail 20 of a railway track, Fig. 2 is an end elevation of the machine with the front part and the engine removed, Fig. 2^a is a detail of the clutch operating mechanism, Fig. 3 is a plan view of the machine complete, Fig. 4 25 is a cross-section of the operating cylinder and spindle mechanism, Fig. 5 is a sectional drawing of the driving mechanism, Fig. 6 shows the relation of the connecting gears between the driving mechanism and the operating cylinder; Fig. 7 is a plan view of a 30 single element machine and Fig. 8 is a side elevation of a single-element machine.

The drawings in this application show the invention applied as a power wrench 40 for tightening the bolts of a rail joint on a railway track. The machine is driven by a gasoline motor which has a shaft parallel with the rail and which, by bevel gears, drives a pair of shafts at right angles to the rail. The latter are provided with friction 45 clutches and suitable spur gears by which the shafts in the operating cylinders are driven. An operating arm is connected with each cylinder provided with a handle 50 by means of which it may be positioned and rotated through an arc of a circle. At the end of this arm the wrench or tool is attached and may be swung opposite any point in the side of the rail; the arm may,

also, be moved out from the rail to fit the 55 tool to the work. When the tool has been fitted to the work the friction clutch is brought into engagement by a hand lever and the torque applied to the tool is regulated by the pressure on the friction clutch. 60 A separate cylinder is provided for the arms operating on each side of the rail.

The machine is constructed along the lines disclosed in U. S. Patent 1,408,872 issued in my name on March 7th, 1922. The 65 machine is mounted upon rollers for rolling it along the rail or track. These rollers have eccentric bearings for adjusting the height of the machine which is balanced and is symmetrical about the centre line so 70 that it may be turned around with either arm on either side of the rail. When removed from the track the operating arms may be turned into a horizontal position so that the machine may stand on the ground 75 without obstruction. When used for working on the rail of a railroad track this machine is designed so that it is not rigidly connected to the rail when it is not being operated and thus it can readily be removed 80 by the pilot of a passing train without the possibility of accident.

In the drawings 11 represents the rail of a railway track, 12 and 13 are the splice bars or angle bars for jointing the ends of two 85 rails, 17 is a bolt for securing the splice bars in place and 15 is the nut of a similar bolt pointing in the opposite direction. The common practice is to alternately point the bolts in opposite directions for the larger 90 size of rails and to point the bolts in the same direction for the smaller size of rails. The bolt is usually provided with an oval neck for which an oval hole as indicated at 16 is provided in the splice bar.

The frame of the machine is indicated at 21 which extends parallel with the rail and is supported on the rollers 22 at each end which are flanged to roll along the rail. These rollers are provided with eccentric 100 bearings 23 to provide adjustment for the height of the machine above the rail. The frame 21 has a T-flange 24 at the top to which the parts of the mechanism are bolted. The source of power is indicated by the 105 gasoline motor 25 having the fly wheel 26 to which the shaft 61 supported in bearing 62 is secured by the flange 63. The upstand-

ing brackets 27 and 28 are secured to the frame at right angles to the rail and support the driving mechanism. The central bracket 29 supports and encloses the bevel gears of the driving mechanism. 30 and 31 are operating cylinders by means of which the operating tool is driven and directed.

The construction of the operating cylinder and tool is shown in Fig. 4. The sleeve 10 30 is secured in a saddle in frame 21. The plunger 35 slides in this sleeve to the extent of the slot 36, and at the same time is free to rotate therein. A coil spring 38 abutting on the end plate 39 tends to move plunger 15 35 outward until stopped by the ring cushion 37. A shaft 40 passes through the centre of the cylinder and is provided with a spline 41 at one end which is engaged by the key 42 fitting in a key way in the spur gear 43 20 which is enclosed by the end plate 44. The opposite end of shaft 40 has a bearing in hub 45 against which the end thrust is taken up by collar 46 on one side and by the bevel gear 47 on the other side which is secured to 25 the shaft.

The bevel gear 47 engages the bevel gear 48 secured to shaft 49 which has a bearing in the casing 50. The lower end of shaft 49 carries the bevel gear 51 which engages the 30 bevel gear 52 mounted on spindle 53 which rotates in bearing 54. The spindle 53 carries the tool 55 for operating on the side of the rail and as shown in the drawing this tool comprises a bell-mouthed wrench for 35 tightening the nut 14 of the rail joint.

The casing 50 is provided with a cover 57 having a socket as shown for the operating handle 58 which terminates in the spade handle grip.

40 With this construction it will be noted that rotating the spur gear 43 rotates the spindle 53 at a reduced speed at the same time the plunger 35 may be moved back and forth in sleeve 30 and the handle 58 may be rotated moving the arm 50 and the spindle 53 in an arc at the side of the rail. The spring 38 tends to move the tool 55 away from the rail and thus disengage the mechanism from the rail. When brought into 45 operation the plunger 35 is moved by the handle 58 against spring 38 until the wrench engages the nut.

The driving mechanism will be understood from Fig. 5. The driving shaft 61 has the 55 bevel gear 64 secured thereto which meshes with the bevel gear 65 rotating on shaft 67 and the bevel gear 66 rotating on shaft 69. The gears 65 and 66 it will be noted rotate in opposite directions. The shaft 67 has a bearing in the hub 71 of the central bracket and at the outer end in bracket 28. The shaft 69, likewise has a bearing in the central hub 71 and in the bracket 27. The bevel gear 65 rotates freely on the shaft and has a 60 frictional disc 73 forming one side of a

friction clutch the other side of which is formed by the disc 74. Preferably a disc or ring of fibrous material is placed between the friction discs as shown to take up the wear. The friction disc 74 is splined to 70 shaft 67 by the key 75 as shown and is held out of engagement with disc 73 by the coil spring 76 abutting against the collar 68 on shaft 67 as shown. Thus, normally, the friction clutch is disengaged. The spur gear 75 83 is secured to shaft 67 which forms the means by which this gear is driven.

The construction of the opposite side is similar to that just described. The friction disc 78 is splined to shaft 69 by key 79 and 80 is held released by spring 80 abutting on collar 70 on shaft 69. The spur gear 84 is secured to shaft 69 and moves integral therewith. The clutch member 74 is provided with a groove 77 by which the clutch members are brought into engagement and a similar groove 81 is provided in clutch member 78.

When the shaft 61 is driven it is apparent that the bevel gears 65 and 66 rotate idly 90 on their shafts. When clutch member 74 is brought into engagement with 73 shaft 67 is rotated together with the spur gear 83. Also, when clutch member 78 is brought into engagement with 72 shaft 69 is rotated 95 together with spur gear 84. The spur gears 83 and 84 rotate in opposite directions and either set of gears may be brought into operation independently of the other set. The torque which is applied to the spur gears 100 will naturally depend upon the amount of slip in the clutch members which in turn depends upon the pressure with which they are brought together.

The friction clutch is operated by a clutch 105 ring 90, Fig. 2, pivoted at 91 and having a pair of pins 92 engaging the groove in the clutch member according to a well known construction for operating clutches. A vertical handle 93 operates the clutch to the left 110 which controls the spindle to the right of the rail and another vertical handle 94 controls the clutch to the right which, in turn controls the tool operating on the left side of the rail.

The driving mechanism is connected with 115 the operating cylinders by an intermediate gear as best shown in Figs. 2 and 3. The spur gear 83 meshes with the intermediate gear 95 pivoted by a stud in the hub 96 on bracket 28; this gear in turn meshes with the 120 spur gear 43 of cylinder 30. The relation of these gears is shown in the elevation in Fig. 6, in one cylinder the gear 43 is located to the right of the driving gear and in the other cylinder this gear is located to the left 125 of the driving gear corresponding to the relation of the cylinders to the driving mechanism. In the same manner, the spur gear 84 meshes with the intermediate gear 97 pivoted on a stud secured at 98 to bracket 27 130

and in turn this gear meshes with the spur gear 43 of cylinder 31. By this construction it will be observed that the spindle associated with cylinder 30 is driven from shaft 61 through friction clutch 74 and the spindle associated with cylinder 31 is also driven from shaft 61 through the friction clutch 78. The machine just described is known as the double type in which a plurality of arms 10 with operating tools may be independently and simultaneously brought to operate upon the rail and if the work is to be performed on both sides of the rail the operating tools are placed on both sides with independent 15 controls and drives for each tool. As shown the machine is symmetrical about its longitudinal centre, each operating cylinder being alike and each side of the driving mechanism being alike and interchangeable. It will be 20 noted that the centre of gravity of the machine falls on the centre line directly above the rail so that it is balanced on the rollers and can be rolled along the track with comparatively little effort. 25 It often happens that the bolts are not fully driven up to the head and require a blow from a hammer for this purpose before the nut is tightened. A tool is provided on the machine which performs this work as 30 shown in Figs. 1 and 2. This tool comprises the weighted head 102 supported by the arm 103, pivoted at 104 to the frame 21 and has the lever extension 105 with a pedal at its extremity. A coil spring 106, Fig. 1, holds 35 the head 102 normally away from the bolt. By the movement of the pedal the head 102 can be used as a hammer which operates in alignment with the bolt head. The lever 105 may, of course, be extended for hand operation. 40

The head 102 may be shaped to suit the head of the bolt; for instance, if the bolt head were hexagon, 102 might be used to prevent the bolt from turning. A tool of 45 this kind is provided opposite each operating arm as indicated at 103 and 103^a in Fig. 1. The tool 103^a is pivoted at 108 to the frame 21 approximately opposite the working position of the arm controlled by handle 58. The heads 102 are elongated to provide 50 for considerable displacement of the machine on the rail.

A horizontal pipe railing is provided 55 around the machine to form a convenient handle by which it may be steadied and rolled along the track, which forms a protection to the exposed parts and which forms a support for the controlling mechanism of the motor, the friction clutches and other 60 parts.

This railing comprises a pair of vertical pipes 111 secured in sockets to one end of the frame and another pair of vertical pipes 112 similarly secured at the other end of the frame. The horizontal rails 113 and 114 are

supported by the vertical pipes. In order that the clutch levers 93 and 94 may be conveniently operated by the person manipulating the handles 58 and 58^a these levers are controlled by remotely located handles as 70 shown in Figs. 2 and 2^a. Lever 93 is connected by a rod 115 with the handle 116 pivoted to frame 114 opposite handle 58. Also, lever 94 is connected by rod 117 with bell crank 118 and by connection 119 to handle 120 close to the operating position of handle 58^a. As shown in Fig. 1, the bell crank 118 and the handle 120 are pivoted to the pipe railing 112.

In tightening the bolts of a rail joint by hand a long handled wrench is used by which the operator obtains considerable leverage on the nut and the tightness of the nut can be gaged by its resistance. The degree to which a nut should be tightened varies with 80 the spring in the splice bars, the weather conditions, the nature of the bolt, etc., and the operator can, by feeling the resistance of the nut determine the degree of tightness desired. The ability to determine by feeling 90 the tightness of a nut has been preserved in the power operated machine, disclosed in the present invention. The operator when using the machine, directs the tool by the handle 58 and when it has been properly positioned pressure is then applied to the clutch through the clutch handle. The extent to which this pressure should be applied for the required tightness of the nut can be determined with a little practice. 100

The double machine is intended to be used by two operators, one on each side of the machine, controlling an operating arm, each operator being able to carry on his work independently of the other. The single machines are, however, operated by one person and are light enough to be removed from the rail by one person to clear the track for a passing train. 105

It has been shown that the mechanism drives the spindles of the operating arms on each side of the rail in opposite directions as is necessary to tighten the nuts on both sides of the rail. It will be observed that each spindle may operate on the same bolt; for instance, if the bolt rotated and had a hex head, the bolt and the nut could both be rotated at the same time in opposite directions. 110

A considerable part of the utility of this machine when used as a power wrench resides in the quickness with which it may be brought into action at the points desired. The machine is rolled along the rail until a joint is reached, then the wrench must be aligned with the nut which always occupies a fixed position in the rail. For this purpose the machine moves on its rollers and for vertical adjustment the operating arm is rotated about the cylinder. The wrench, being bell-mouthed readily "finds" the nut and 115 120 125 130

the spindle automatically centers itself on the nut by the movement of the arm or the movement of the machine on its rollers or by a combination of these movements. This condition of centering is also aided by the reaction from the spindle which tends to rotate the depending arm about the spindle and which is resisted by the weight of the machine. The operating arms are designed 10 to operate in a position inclined to the vertical so that the combined rotary and rolling motion will readily accommodate themselves to the strain on the spindle. This construction is considered superior to splining shaft 15 49 and making the radius of the operating arm adjustable.

The operations described relate to the tightening of nuts but it is apparent that this machine will reverse its operation and un- 20 screw nuts by rotating the spindles in the op- 25 posite direction. A reversing mechanism has not been provided because it is simpler to reverse the running direction of the motor which, if of the two cycle type will run in either direction, or if an electric motor drive 30 is used a reversing switch will control its direction of running.

Having thus described my invention, I claim:

30 1. In combination, for operating upon a single rail of a railway track having splice bars with a plurality of bolts in said bars with their heads turned alternately in op- 35 posite directions, a power operated wrench for said bolts comprising a frame with a motor arranged to roll upon said rail, a pair of arms depending from said frame, one on each side of said rail, a wrench socket on each arm arranged to engage said 40 bolts, driving means connecting said motor with each of said wrench sockets and a man- 45 ually controlled friction clutch interposed in each drive.

2. In combination, for operating upon a single rail of a railway track having splice bars with a plurality of bolts, a power operated wrench for said bolts comprising a frame with a motor arranged to roll upon said rail, a pair of arms depending from 50 said frame, one on each side of said rail, a wrench socket on each arm arranged to engage said bolts, means manually sustained for independently connecting each socket with said motor and means for normally 55 disconnecting said sockets from said motor.

3. In combination, for operating upon a single rail of a railway track having splice bars with a plurality of bolts, a power operated wrench for said bolts comprising a frame with a motor and fly wheel arranged 60 to roll upon said rail, a pair of arms depend- 65 ing from said frame, one on each side of said rail, a wrench socket on each arm arranged to engage said bolts, means opera- 70 tively connecting said wrench sockets with

said motor and a lever controlled friction clutch for regulating the tension on each of said wrench sockets.

4. In combination, for operating upon a single rail of a railway track having splice 70 bars with a plurality of bolts, a power operated wrench for said bolts comprising a frame with a motor and fly wheel arranged to roll upon said rail, a pair of shafts at right angles to said rail geared to said motor 75 and arranged to turn in opposite directions, a pair of arms depending from said frame, one on each side of said rail, a wrench socket on each arm arranged to engage said bolts and manually sustained friction clutches op- 80 eratively connecting each of said sockets with said shafts.

5. A machine for working on a single rail of a railway track comprising a frame with a motor thereon, a driving shaft par- 85 allel with said rail connected with said motor, a driven shaft at right angles to said rail geared to said driving shaft, a friction clutch associated with said driven shaft, a splined shaft connected with said driven 90 shaft, an arm depending from said frame, a spindle in said arm arranged to work on the side of said rail and means operatively connecting said splined shaft with said 95 spindle.

6. In combination, for operating upon a rail of a railway track having splice bars with a plurality of bolts, a power operated wrench for said bolts comprising a frame with a motor arranged to roll upon said rail, 100 a pair of independent shafts geared to said motor, a pair of cylinders, a pair of arms depending from said cylinders, one on each side of said rail, a wrench socket on each arm arranged to engage said bolts and 105 means, including said shafts, operatively connecting said sockets with said motor and so arranged that said sockets turn in oppo- 110 site directions.

7. A machine for working on a rail of the 110 class described comprising a frame with a motor at one end, a driving shaft connected with said motor parallel with said rail, a pair of driven shafts in the same axial plane at right angles to said rail independently 115 connected with said driving shaft, a pair of cylinders located one on each side of said driven shafts, a central shaft in each of said cylinders connected with said driven 120 shafts and an operating tool connected with each of said central shafts.

8. A machine for working on a single rail of the class described comprising a frame with a motor arranged to roll upon the rail, a driving shaft connected with said motor par- 125 allel with said rail, a pair of driven shafts at right angles to said rail geared to said driving shaft, a pair of cylinders secured to said frame, a plunger in each of said cylinders supporting said driven shafts, a pair 130

of arms depending from said frame on opposite sides of said rail, an operating spindle supported by each of said arms and driving means connecting said spindles with said shafts.

9. A machine for working on a single rail of a railway track comprising a frame with a motor mounted to roll upon the rail, a driving shaft connected with said motor parallel with said rail, a pair of driven shafts in the same axial plane, a bevel gear connecting said driving shaft with said driven shafts and so arranged that said driven shafts rotate in opposite directions, a pair of tools, one on each side of said rail and means operatively connecting said tools with said driven shafts.

10. A machine for working on a single rail of a railway track comprising a frame with a motor balanced upon the rail, a driving shaft connected with said motor parallel with the rail, a pair of shafts at right angles to the rail geared to said driving shaft, a pair of arms depending from said frame, one on each side of said rail, a sliding support for said arms, a spindle in each arm and means operatively connecting said spindles with said driven shafts so that they rotate in opposite directions.

11. A machine for working on a single rail of the class described comprising a frame mounted upon rollers to roll upon the rail, a driven shaft on said frame parallel with said rail, a pair of cylinders with depending arms for operating one upon each side of said rail and connected with said

driven shaft, said machine being symmetrical about its longitudinal centre.

12. In a bolt and nut turning machine, in combination; a frame; supporting wheels revolvably attached to said frame for resting on a rail; a power generator mounted on said frame; wrenches depending from said frame one on each side thereof; means supporting said wrenches allowing each wrench to describe an arc of a circle and to move at substantially a right angle to the rail upon which the wheels rest; means for driving and connecting said wrenches with the power generator, all arranged symmetrically about the longitudinal centre line of said frame and about a vertical plane passing through the longitudinal centre line of the rail upon which the supporting wheels rest.

13. In a machine for operating upon the splice bar bolts and nuts of a rail line, the combination of manually positioned wrenches, one disposed on each side of said rail line in different vertical planes at right angles to the rail line and means for connecting to, supporting and power operating said wrenches so that one rotates in one direction and the other in the opposite direction all symmetrically disposed about a vertical plane passing through substantially the longitudinal centre line of the rail line being worked upon.

Signed at New York in the county of New York and State of New York this 10th day of July A. D. 1923.

EDWARD A. EVERETT.
